REPEATING FUSE APPARATUS

George N. Lemmen, Birmingham, Ala.

Application December 14, 1936, Serial No. 115,825

16 Claims. (Cl. 206—126)

This invention relates to repeating fuse apparatus, particularly of the general character described in my prior Patent No. 1,954,633, and the joint patent issued to myself and Harry H. Knowles, No. 1,954,634, on April 10, 1934.

The particular objects of my present invention are to provide apparatus of the character described which shall have an improved latching means for the fuse holder whereby when it is forced into service position the latch will engage without danger of falling; to provide an improved protective means for the latches and for the fuse holder operating mechanism whereby they will not be affected by snow and sleet; to provide an improved assembly for actuating the fuse holders and causing them to move without possibility of failure, to service position from reserve position, and to move from service position to fuse ruptured position; and to provide an improved cocking and trigger release mechanism for the fuse holder carriages.

In the drawings forming a part of this application,

Fig. 1 is a side elevation of my improved repeating fuse apparatus with the lower part in section along the line I—I of Fig. 3;

Fig. 2 is a detail view showing the release of the upper latch of a fuse holder upon rupture of a fuse;

Fig. 3 is a front elevation of my improved apparatus with some parts of the tripping mechanism omitted for the sake of clarity;

Fig. 4 is a detail sectional view taken along the line IV—IV of Fig. 3, showing the fuse holder in fuse ruptured position;

Fig. 5 is a sectional view taken along the line V—V of Fig. 3, showing one fuse holder in reserve position, and one in fuse ruptured position;

Fig. 6 is a perspective view taken from above and showing a part of the cocking and trigger release mechanism for the fuse holders removed from the housing;

Fig. 7 is a sectional view taken along the line VII—VII of Fig. 3;

Fig. 8 is a detail sectional view showing a part of the trigger release mechanism for a fuse holder;

Fig. 9 is a fragmentary detail view taken along the line IX—IX of Fig. 3, showing a part of a fuse holder carriage with the latching means for the fuse holder in section; and

Fig. 10 is a side elevation of the lower casting, showing its preferred position with respect to the horizontal when in service.

Referring to the drawings, my improved ap-

paratus comprises an upper casting 10 to which an electric line wire may be connected, as at 11, and a lower casting 12 having means 15 for connecting a line wire thereto. The castings 10 and 12 are connected respectively to insulators 13 and 14, which latter are joined together, end to end, by means of a stud 16 and nuts 17 and 18. Straps 19 and 21 also are connected to the stud 16 by means of the nuts 17 and 18, and are joined together by a bolt 22, and may serve as a means for mounting the apparatus.

Electric current passes from the casting 10 to the casting 12, or oppositely, through one of a plurality of fuses carried by fuse holders 23, 24 and 26, only one of which is in service at a time, 15 as is well understood. Each of the fuse holders 23, 24 and 26 comprises a hollow tube 27 of insulating material through which is passed a fusible connector 28. On the upper end of each tube is a terminal 29, and on the lower end a 20 terminal 31, which terminals are secured in any proper manner to the tube 27.

The terminal 29 has a rearwardly extending portion 32 to which is pivotally connected a link 33. Connected to the other end of the link 33 is 25 a latch and contact member 34. The latch member 34 has a forwardly extending portion 36 which, when the fusible member 28 is intact, is held in place thereby, and rests on the upper end of the holder 26, as seen in Fig. 1. Carried by 30 the member 34 is a clamp 37 operated by thumb screw 38, and which is adapted to bear downwardly on the upper end of the fusible member 28, as shown in the drawings. The clamp 37 serves to hold the upper end of the fusible member 35 28 in place, while the latter holds the member 34 against movement relative to the fuse holder.

The casting 10 is formed with a plurality of hoods or recesses 39, corresponding to the number of fuses included in the assembly. Each of the hoods 39 has pivoted at its front, at 40, a latch member 41 which extends rearwardly beneath the hood, to be engaged by the latch member 34 when the fuse holder 26 is in service position. The latch member 41 is normally pressed downwardly by a spring 42, and is prevented from moving with the hood 39 downwardly too far by engagement of its heel 43 forwardly of the pivot 40. When a fuse holder moves from reserve to 50 service position, the member 34 acts to compress the spring 42 and move the latch 41 out of the way and engage it after it passes. The forward pivoting of the latch 41, and the arrangement of the spring 42, are important in that they provide 55

a sure latching means for the fuse holders 23, 24 and 26, when they are moved to service position. As will be seen hereafter, the fuse holders move to service position very rapidly, and unless the latch member 41 moves almost instantaneously to engage the latch member 34, the fuse holder may jump out and fail to connect.

Also carried by each of the castings 10 and extending downwardly through a slot in the hood 39 is a brush contact member 44 which, as may be seen from Fig. 1, engages the latch and contact member 34 when the fuse holder 26 is in service position. When the fusible member 28 is ruptured, it allows the member 34 to tilt upwardly and rearwardly, as may be seen in Fig. 2, so that the member 34 is no longer engaged by the latch member 41 and the fuse holder 26 then drops out of service position by gravity.

The terminal 29 is also formed with a forwardly extending portion 45 having an opening 47 into which may be inserted a suitable insulated tool for handling the fuse holders when the apparatus is in service.

The construction of the lower casting 12 and the fuse holder operating mechanism will now be described. The lower casting 12 is formed with a continuous cover 48 upturned at its forward edge 48. With the apparatus mounted as shown in Fig. 10, with respect to the horizontal, it will be seen that any rain, snow or sleet which strikes the cover will be deflected by the lower forward edge 48 and drain to the sides and ends and will not drip down into the operating mechanism housed within the lower casting. The casting 12 is divided into compartments by end walls 49 and 51, and partition walls 52 and 53. Mounted within each of the compartments thus formed is a carriage 54. Each of the carriages 54 is mounted upon a shaft 56 which extends through the lower casting 12. Each carriage 54 is biased toward movement in a clockwise direction, as viewed in Figs. 1, 4 and 5, by means of a spiral spring 57 which has one end secured, as may be seen in Figs. 5 and 7, to a lug 58 formed in the casting 12, and the other end secured at 59 to the carriage 54.

Each of the carriages 54 is substantially U-shaped in construction and of a size to fit within its compartment in the casting 12. Each of the 50 carriage side walls, on the inner side, as seen in Fig. 9, is formed with ridges 61 and 62, the latter forming a recess 63 into which is mounted a hinge member, or trunnion, on the fuse holder, as may hereafter be seen.

The terminal 31 of each fuse holder is provided with a rearwardly extending portion 64 carrying a lower trunnion 66 adapted to be engaged with the rib 62 in the recess 63, and an upper trunnion member 67 adapted to engage with the 60 rib 61 in the side wall of the carriage 54 to prevent the fuse holder from jumping out of position when it is being moved from reserve to service position and from service position to fuse ruptured position. Also formed on the member 65 64 is a notch 68 adapted, when the fuse holder is in reserve position, to be engaged by a hook 69 pivotally mounted at 71 in the carriage 54, as may be seen in Figs. 5 and 9. The hook 69 is biased downwardly, as seen in Fig. 9, by a 70 spring 72 mounted in a suitable opening in the hook 69, and extending through an opening in the rib 62. At the rear of the hook 69 is a boss 73 adapted, when the fuse holder is in service position, as seen in Fig. 1, to engage the top of the casting 12 and disengage the hook 69 from

the notch 68, thereby permitting the fuse holder 26 to fall out of service position when the fusible member 28 is ruptured. The hook member 69 is also provided with a forward laterally extending ear 74, which as may be seen by reference to the fuse holder 24 in Fig. 3, when the carriage 54 is rotated counterclockwise beyond the reserve position shown in Figs. 3 and 5, engages with a pin 76 in the side wall of each compartment, thus lifting the hook 69 out of the notch 68, and thus permits the fuse holder to swing down to fuse ruptured position and be removed and replaced after being placed in reserve position.

The rearwardly extending member 64, as may be seen in Fig. 1, carries a screw 77 for securing 1 the lower end of the fusible member 28. It is also provided with a suitable contact surface 78 which, when the fuse holder is in service position, is adapted to be engaged by a flexible contact 79 mounted in the casting 12. Also, the rearwardly 2 extending member 64 carries a trip member 81 which is adapted to engage with and release the carriage operating mechanism, to be described later.

Each of the carriages 54 is provided with a 2 rearward latch engaging member 82 which, when the carriage is moved to reserve position, engages with a latch member which is pivotally mounted in each compartment. The latch member for the left hand carriage is numbered 83a, that for the 31 intermediate carriage 83b, and that for the right hand carriage 83c. The carriages 54 may each be moved to reserve position against the force of the springs 57, by means of a handle 84 carrying a hook 86 which may be engaged by a suitable 34 tool to pull the carriage to reserve position.

Referring now particularly to Figs. 6, 7 and 8, I show the setting and tripping mechanism for the carriages 54 separate from the other parts. The trip member 83a for the left hand carriage 44 54, as seen in Fig. 6, is mounted upon a shaft 87 which extends from end to end through the casting 12 and is secured to said shaft. Formed integrally with the trip member 83a is a manually operable trigger 88 which extends downwardly beneath the casting, as may be seen in Fig. 7. A lug 90 formed in the casting 12 limits the rearward movement of the trigger 88.

Mounted on the opposite end of the shaft 87, in the right hand compartment of the casting 50 12, is a trip member 89, the construction of which is shown in detail in Fig. 8. The trip member 89 is pivoted at 91 to an arm 92 and is limited in its clockwise rotation on the arm 92 by means of a stop pin 93. The arm 89 is biased toward 55 the stop pin 93 and the arm 92 is biased downwardly, as seen in Fig. 8, by means of a spring 94 which engages with the arm 89 and the upper part of the casting 12. The arm 89 is in the path of movement of the trip member 81 provided on the lower end of the terminal 31. The arrangement of the arm 89, just described, permits the trip member 81, when the fuse holder is being mounted in the carriage, and moved to service position, to flex the arm 89 counter-clockwise and pass.

When the fusible member 28 is ruptured, as seen in Fig. 2, and the fuse holder 26 swings downwardly about its pivot counter-clockwise by gravity, the trip member 81 then engages the 70 arm 89, but as the arm 89 can not rotate in a clockwise direction relative to the arm 92, due to the stop pin 93, it rotates the shaft 87. It will thus be seen that if the fuse holder 26, as seen in Figs. 1 and 2, starts to move counter-clockwise, 75

it will release the carriage 54 which is held by the stop member 83a on the opposite end of the shaft 87, which would be the left hand carriage, as seen in Fig. 3.

5 The stop member 83c for the right hand carriage is formed upon a casting 98 which is mounted for rotation upon a shaft 97 mounted in the intermediate partition walls of the casting 12. Formed integrally with the casting 98 and stop member 83c is a manual trip trigger 85 and an arm 88, carrying a trip arm 89, similar to that already described. The casting 98 extends through the intermediate partition wall 52 so that its associated arm 89 is in the path of 10 movement of the trip member 81 carried by the fuse holder 24.

Thus, movement of the fuse holder 24 in a counter-clockwise direction from service position causes the trip member 81 to engage with the arm 89 and release the right hand carriage 54, as seen 15 in Fig. 3. The stop member 83b for the intermediate carriage 54, carrying the fuse holder 24, is formed upon a casting 99, likewise mounted upon the shaft 97, and formed integral with the stop member 83 for the intermediate carriage. The casting 99 likewise has an arm 101, to which is pivoted a trip arm 89, and has formed integrally with the casting a manually operated trigger 102. The casting 99 extends through the 20 partition wall 52 so that its arm 89 is in the path of movement of the trip member 81 carried by the fuse holder 23. Thus, when the fuse holder 23 moves from service to fuse ruptured position, the trip member 81 engages with the arm 89 of 25 the casting 99 and moves the stop 83b out of the path of the latch 82 of the intermediate carriage, thereby permitting the intermediate carriage to move the fuse holder 24 to service position.

40 The operation of my improved apparatus will now be described. Assume all of the fuse holders 23, 24 and 26 removed from the apparatus for re-fusing. The fusible members 28 are put in place and clamped by means of the screws 38 and 77, as shown in Fig. 1 of the drawings. The hooks 36 on the handles 84 of the carriages 54, are next engaged, using a suitable insulated tool therefor, to pull the handles down against the force of the springs 57, until the latch engaging 45 member 82 of each carriage engages with its associated stop member 83a, 83b, or 83c. The carriages are then in reserve position. The fuse holders 23, 24 and 26 may now be mounted in place in the carriages 54. This is done by entering 50 the trunnion 68 of the lower terminal 31 of each fuse holder, in the recess 63 formed by the ribs 62 in the side walls of each carriage. It will be observed that the carriage must be pulled down to reserve position and cocked before the 55 fuse holder can be mounted as just described. Otherwise, it would engage the flexible contact member 79 before the trunnions could enter the recess 63.

As so far described, the fuse holders are assumed all to be in the position of the fuse holder 23 in Fig. 3 of the drawings. Each of the fuse holders is next rotated about its trunnion 68 as an axis, until the hook 69 engages with the notch 68 on the terminal 31, as seen in Fig. 5. 60 Each of the fuse holders is then in reserve position, ready to be thrown to service position by the force of its associated spring 57. One of the manually operated triggers, for example, trigger 88, is next pulled, which releases the carriage for 65 fuse holder 23 and causes it to move to service

position. Just before it reaches service position, the boss 73 of the hook 69 strikes the upper part of the casting 12 and releases the hook, so that the fuse holder is carried to its final latched position, as seen in Fig. 1, by its own momentum. 70

Assuming now that the fusible member 28 of the holder in service position, is ruptured. The fuse holder starts to swing by gravity and the member 84 tilts rearwardly to disengage from the latch 41, as seen in Fig. 2. Inasmuch as the hook 69 is disengaged from the notch 68, the fuse holder is free to fall down to the position of the fuse holder 23 in Fig. 3. As it moves downwardly, the trip member 81 engages the arm 89 in the left hand compartment, as seen in Fig. 3, 15 causing the stop member 83b of the intermediate carriage to move out of engagement with the latch engaging member 82, thus releasing the intermediate carriage and allowing the fuse holder 24 to be moved to service position, as just described. 20

When the fuse in fuse holder 24 is ruptured, it drops out of place and, striking the arm 89 in the intermediate compartment, moves the stop member 83c out of engagement with the latch engaging member 82 in the right hand compartment, causing the fuse holder 26 to move to service position. When the fuse in fuse holder 26 is ruptured, all the fuse holders must be again re-fused and their carriages set to reserve position before the apparatus can again operate. It is, of course, understood that the apparatus will be inspected at regular intervals and ruptured fuses replaced so that there will be continuity of 25 service, unless there is a sustained fault which causes a rupture of all three fuses at one time. 30

In describing the sequence of operation of the fuse holders I have stated, by way of illustration, that the fuse holder 23 is caused to be operated first, followed by the fuse holders 24 and 26. It will be obvious from the preceding description that any one of the three fuses may be put in service position first and it will be followed in its operation by the other two. 40

While I have shown my invention in but one form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims. 45

What I claim is:

1. In repeating fuse apparatus of the character described, a supporting insulator, a metallic base member attached to the said insulator, a plurality of tubular fuse holders movably mounted on the under side of the said base member, and operating mechanism for moving the fuse holders, the said base member constituting a protecting cover over all the said operating mechanism. 55

2. An expulsion-tube fuse device which includes two gap-spaced insulated terminals, a tube spanning the gap, and latch means upon one of said terminals to retain the tube in gap-spanning position, the said latch means comprising a stationary protecting cover and a movable member pivotally mounted beneath the cover and with its tube-retaining portion extending inwardly from its pivotal mounting. 60

3. In apparatus of the character described, two rigid spaced insulated terminals one above the other, a fuse holder pivotally mounted in the lower terminal, spring actuated trigger release 75

- means for moving the fuse holder into circuit closing position with the upper terminal, and latch means carried by the upper terminal for engaging and holding the fuse holder in circuit closing position comprising a spring pressed pivoted latch inclined to the path of movement of the fuse holder, with its pivot in advance of its engaging portion relative to the fuse holder when moving to service position.
10. 4. In apparatus of the character described, a base casting, a cover for the casting which in service is inclined to the horizontal, an upwardly turned lip on the lower edge of the casting, end walls for the casting, a fuse holder operating mechanism mounted in the casting entirely beneath the cover, and a fuse holder pivotally mounted in the carriage and swung upwardly to service position from the lower open side of the base casting.
15. 5. In a repeating fuse apparatus, a base associated with a mounting bracket, a series of independent spring pressed fuse holders, a latch housing mounted rigid with the base, and a series of spring responsive latches mounted under the housing with their free ends each disposed in the path of a fuse holder and in the direction of its movement to service position.
20. 6. In a repeating fuse apparatus, a base associated with a mounting bracket, a series of independent spring pressed fuse holders, a latch housing mounted rigid with the base, the housing being designed to protect the latch means from access of water, and a series of spring actuated latches mounted under the housing with their free ends each disposed in the path of a fuse holder and in the direction of its movement to service position.
25. 7. In a repeating fuse apparatus, a base associated with a mounting bracket, a series of independent spring pressed fuse holders, a latch means for holding said fuse holders in service position, said base being designed and adapted to overhang and shed water away from the spring mounted ends of said fuse holders, and a series of spring responsive latches mounted under the housing with their free ends each disposed in the path of a fuse holder and in the direction of its movement to service position.
30. 8. In repeating fuse apparatus, two rigid spaced insulated terminals one above the other, a plurality of fuse holders pivotally mounted on the lower terminal, spring actuated trigger release means for moving the fuse holders successively into circuit closing position with the upper terminal, and latch means carried by the upper terminal for engaging and holding the fuse holders in circuit closing position comprising spring pressed pivoted latches inclined to the path of movement of the fuse holders, with their pivots in advance of their engaging portions relative to a fuse holder moving to service position.
35. 9. In repeating fuse apparatus, an upper rigid terminal casting, a plurality of fuse holders, said upper terminal casting having covered recesses therein for receiving the upper ends of said fuse holders, spring pressed latches located in said recesses for engaging the fuse holders, a lower rigid terminal casting, a cover over the lower casting, a plurality of spring actuated fuse holder carriages mounted for operation in the lower casting beneath the cover, means for pivotally mounting the fuse holders in said carriages, and means for successively operating the carriages to swing the fuse holder upwards and engage the latches.
40. 10. In a repeating fuse apparatus, a base casting, a plurality of spring actuated carriages mounted for angular movement in said casting, cocking and trigger release mechanism for each of said carriages, a fuse holder detachably mounted in each of said carriages, means on each fuse holder to actuate the trigger release of another carriage, an upper rigid casting having a plurality of recesses therein for receiving the upper ends of the fuse holders, and pivoted spring 10 pressed latches disposed in each of said recesses to engage and retain the fuse carriers when they are moved to service position, the pivots for said latches being in advance of the engaging means relative to the path of movement of the 15 fuse holders.
45. 11. In a repeating fuse apparatus, a covered base casting, a plurality of spring actuated carriages mounted for angular movement in said casting, cocking and trigger release mechanism 20 for each of said carriages disposed beneath the cover of the casting, a fuse holder detachably mounted in each of said carriages, means on each fuse holder to actuate the trigger release of another carriage, an upper rigid casting having a plurality of recesses therein for receiving the upper ends of the fuse holders, and pivoted spring 25 pressed latch means disposed in each of said recesses to engage and retain the fuse carriers when they are moved to service position. 30
50. 12. In repeating fuse apparatus of the character described, a base casting, a cover for the casting which in service is inclined to the horizontal, an upwardly turned lip on the lower edge 35 of the casting, end walls for the casting, a plurality of fuse holder operating mechanisms mounted in the casting entirely beneath the cover, and a plurality of fuse holders pivotally mounted in the mechanisms to swing upwardly to service position from the lower open side of 40 the base casting.
55. 13. In repeating fuse apparatus of the character described, a base casting, a cover for the casting which in service is inclined to the horizontal, an upwardly turned lip on the lower edge 45 of the casting, end walls for the casting, a plurality of fuse holding operating carriages mounted in the casting beneath the cover, a plurality of fuse holders pivotally mounted in the carriages to swing upwardly to service position from the 50 lower open side of the base casting, an upper casting insulated from the base casting, a plurality of covered recesses in the upper casting in the paths of movement of the fuse holders when moving to service position, latch engaging means 55 on the upper ends of the fuse holders, and pivoted latches in the recesses for engaging the latch engaging means, the pivots for said latches being disposed forwardly thereof with respect to the paths of movement of the fuse holders. 60
60. 14. In combination, two gap-spaced insulated bases, a plurality of tubular fuse holders movably mounted upon the first of said bases and movable into and out of contact with the second of said bases, a single cover for the said first 65 base independent of the said second base, together with operating mechanism for the said fuse holders mounted wholly beneath the said cover upon the said first base.
65. 15. In combination, in electrical fuse apparatus, two gap-spaced insulated terminals, an insulating tubular fuse container mounted on one of said terminals and movable into circuit-closing position across the said gap, automatic closing means to move the container from open-cir- 70 75

cuit towards closed-circuit position, together with means to discontinue the control of the said closing means over the said container, by the time the said container has reached fully closed position.

16. In combination, in electrical fuse apparatus, two gap-spaced insulated terminals, an insulating tubular fuse container mounted on one of said terminals and movable into circuit-clos-

ing position across the said gap, spring-actuated means to initiate the motion of the container from open-circuit to closed-circuit position, and means to disconnect the spring actuated means before the container reaches closed-circuit position whereby the said motion is completed solely by the momentum of the said container.

GEORGE N. LEMMON.
